YARN CARRIER CONTROLLING
MECHANISM

Edgar F. Hathaway, Wellesley, Mass., assignor
to Shawmut Engineering Company, Dor-
chester, Mass., a corporation of Massachu-
setts

Application March 4, 1930. Serial No. 433,003

11 Claims. (Cl. 139—7)

My present invention relates to looms wherein a plurality of yarn carriers or tube-frames supporting spooled yarns are successively presented in operative position, such as looms for weaving tufted fabrics, including carpet looms; more particularly, it aims to provide improved means for conveying the carriers or frames to and from yarn presenting position, and for insuring their proper travel and presentation.

10 In the drawing illustrating one form of mechanism embodying the invention,

Fig. 1 is a side elevation of a portion of the conveying mechanism, showing one wheel or sprocket and a section of the pattern or carrier chain passing about it;

Fig. 2 is a vertical section through the mechanism of Fig. 1, looking toward the right in said figure;

Fig. 3 is a partially diagrammatic view showing the general arrangement of carrier chain and its supporting framework; and

Fig. 4 is a vertical sectional view of a chain-supporting and guiding means at the upper part of Fig. 3.

25 Referring first to Fig. 3, a portion of the loom frame is seen at 1. The framework or overhead structure for supporting the carrier or pattern chains includes the uprights 2 and the longitudinal beam 3, a portion of which is also seen in Figs. 1 and 2. The framework carries the upper wheels or sprockets 4 on shafts 5 in suitable bearings 6, and also supports the similar intermediate sheaves or sprockets 7. The chain 8 is looped around the latter in the manner indicated in Fig. 3. Any one or more of the members 4 and 7 may be driven to feed the chain step by step, in either direction as conditions require. Hereafter in the description and claims the term "wheel" is used generically to designate a rotary element about which the conveyor or chain passes.

35 The yarn carriers or tube frames each comprise a longitudinal bar, carrier or frame proper 9 equipped with yarn guides or tubes 10 receiving the yarn ends from the spools 11 journaled in spool brackets 12. The term "frame" is hereafter used in the description and claims as indicating any of the various types or constructions of elements for supporting and directing yarn units in this art, whether equipped with tubular or other guides for the yarns or yarn units. The frames are adapted for releasable attachment to the chains by suitable suspension means herein shown as including the chain-penetrating fingers 13, Figs. 2 and 4, and the co-

operating movable latches or hooks 14. It will be understood that a similar chain and operating mechanism as shown in Fig. 3 is also provided at the opposite loom side, the series of 60 yarn carriers or frames being suspended on any between the chains. The chains illustrated are composed of alternate single and double links, the frames being attached at the double links, as best seen in Fig. 4, while the sprocket teeth engage 65 between the double links, straddling the single links.

In the course of weaving operation the frames 9 may approach their operative position, at the lower left corner of Fig. 3, from either direction, either downwardly along the left-hand run of 70 the loop of chain at the left in said figure, or along the right-hand run of that loop. At different stages in the weaving of a given fabric, such as a rug, the chain and frames may be moved in different directions, as in the case where a pattern comprises portions repeated in reverse arrangement. It will be noted that the frames 9 on the upper run of the chain, between the upper sprockets 4, are above or upon the outside of the 75 chain and in substantially vertical position, with 80 respect to the direction of their yarn guides or tubes 10, while at the vertical runs of the chain the frames are horizontal or somewhat beyond the horizontal, with their tubes or guides pointing 85 downwardly.

By reason of the engagement of the chain-penetrating fingers 13 of the frame suspension means between the ends of the single links, the frames 9 are held substantially perpendicular to the chain, whether the latter is running horizontally or vertically. However, there is necessarily considerable play between the frame suspension means and the chain, to allow for easy movement of the parts in the operation of transferring the frames successively from the chain to 90 yarn presenting position in the loom, and in subsequently returning them to the chain.

95 Because of this play the frames can and do shift or swing angularly with respect to the 100 chain, to either side of the true perpendicular. At some points in their travel this shifting action is particularly marked and objectionable, especially where the chains pass about the upper sprockets and the frames, then at the outside of 105 the chains, go from a vertical run to a horizontal run, or vice versa. At those points the frames frequently flop violently from one angular position on the chain to another. This sometimes causes 110 one or more of them to fall from the chains, or

dislodges spools from the frames, with resultant expensive delays and damaged looms.

In accordance with my invention this objectionable flopping action of the frames is avoided.

5 Referring now more particularly to Figs. 1 and 2, one of the sprockets 4 is there shown upon a larger scale. Associated therewith is an annular series of yoke-like brackets 15 supported for movement with the sprocket, upon the sprocket 10 itself, as illustrated, or otherwise. The brackets 15 include inner and outer arms 16 and 17 in which are slidably mounted the plungers or pins 18. A coil spring 19 surrounds each plunger intermediate the inner arm of its bracket and a 15 collar 20 on the plunger, normally pressing the plunger outwardly into inactive position, wherein its inner end or nose 21 is out of the plane of the chain and its other or outer end projects outside its bracket, as shown at the lower portion 20 of Fig. 2.

Means is provided for moving the plungers inwardly at the proper time to engage and support an adjacent frame, substantially in the manner shown at the top of Fig. 2 and at the right 25 portion of Fig. 1. For this purpose I have shown a face cam 22 of arcuate form and having its active portion concentric with the chain sprocket 4. This cam is stationary in the illustrated mechanism and is supported in any suitable manner, 30 as by attachment to the longitudinal beam 3.

The cam 22 extends over that portion of the sprocket at which objectional flopping of the frames otherwise occurs, that is, through substantially the upper right quadrant of the sprocket as 35 seen in Fig. 1. As each plunger 18 approaches the cam, whichever the direction of the rotation of the sprocket and of the movement of the chain, it rides up onto the cam and is moved into position to receive and support the adjacent 40 frame.

Assume, for example, that the sprocket of Fig. 1 is turning clockwise, so that the chain is moving from left to right at the top of the sprocket. The plunger 18 then at the top center position in 45 Fig. 1 has just been cammed into position to receive the adjacent approaching frame 9. As the chain and frame continue their movement to the right and downwardly in Fig. 1, the frame rests upon and is supported by the extended plunger, 50 which thus prevents it from flopping vigorously from upright to horizontal or depending position. This supporting action, by each plunger in turn, is preferably continued substantially until the chain leaves the sprocket, at which point the 55 plungers gradually move away from their respective previously supported frames, due to the change from curvilinear to straight line movement of the chain and because the frames have then assumed their annular position with respect 60 to the chain which they will hold throughout the succeeding downward run. The plungers then ride off from the cam 22 and are retracted by their springs. In this manner the release of the 65 frames by the plungers is gradual and gentle rather than by an objectionable sudden or dropping action. The mechanism illustrated in Figs. 1 and 2 is typical, and any or all of the chain 70 sheaves or sprockets may be similarly equipped.

In cooperation with the described frame-supporting means at the points of change in direction of chain movement, I may provide additional means for supporting and guiding the chains and the frames carried thereby, and especially the horizontal runs of the chains, as between the upper sprockets 4. For this purpose

there is mounted on the longitudinal beam 3 a plurality of upright posts 30, three of which are seen in Fig. 3. These posts support a longitudinally extending chain-guiding element or bar 31 which rests upon their tops and is yieldingly held in position laterally by spring members 32 having their upper ends attached to the guide bar as by the bolts 33; see Fig. 4. These spring members 32 are riveted or otherwise anchored to the posts or to the beam 3. The guide bar 31 underlies the outer links of the double-link units of the chain 8 and thus prevents it from sagging but is out of the path of the frame suspension members 13, 14. Being laterally yieldable it accommodates any slight irregularities in alignment between the frames and brings them into correct line. The spring members 32 preferably extend above the guide bar 31, as best seen in Fig. 4, and serve additionally to guide the chain crosswise thereof, in the direction lengthwise of 95 the tube frames. Thus the frames are kept accurately in alignment, reducing the liability of their becoming dislodged from the chains and insuring proper interengagement between the 100 chains and the sprockets.

It will be understood that my invention in certain of its aspects is likewise applicable to looms wherein the yarn carriers or frames are not taken from their conveying chains in the process of weaving.

My invention is not limited to the particular embodiment thereof herein illustrated and described, its scope being set forth in the following claims.

I claim:

1. In a carpet or like loom, in combination, pattern chains, a series of yarn frames carried thereby, sprockets over which the chains pass, and a series of plungers normally out of the path of the frames but adapted to be moved into supporting engagement therewith during travel of the latter past a sprocket.

2. Frame conveying mechanism for a pile fabric loom, comprising chains extending in differently directioned runs, a series of yarn frames having carriers proper and having projecting members for connecting them directly to links of the chains, and other means adjacent one or more of the points of change in direction of run of the chains and operatively mounted on the loom 125 additionally to engage laterally and support the frames at their leading sides.

3. In a pile-fabric loom, a plurality of tuft-yarn-spool frames, chains for conveying the frames, wheels about which the chains pass, and means normally positioned outside the chains but projectible across the plane thereof to support the frames adjacent a wheel.

4. In a pile-fabric loom; a plurality of tuft-yarn-spool frames; chains for conveying the frames; wheels about which the chains pass; and frame-supporting and guiding means at one or more of the wheels comprising a series of spring-pressed plungers concentric with the wheel and normally held away from the frames by their springs, and means for moving the plungers into frame-engaging position during a portion of the travel of the frames past the wheel.

5. In a pile-fabric loom, a plurality of tuft-yarn-spool frames, chains for conveying the frames, wheels about which the chains pass, and a plurality of laterally extending members on a wheel adapted to make supporting engagement with passing frames.

6. In a pile-fabric loom, a plurality of tuft-

- 5 yarn-spool frames, chains for conveying the frames, and wheels about which the chains pass, a series of plungers disposed circumferentially of a wheel and respectively adapted to engage passing frames to restrain objectionable movement thereof relative to the chain, and means to actuate the plungers sequentially. 80
- 10 7. Conveying mechanism for tufting frames of looms, comprising carrier chains, wheels for supporting and moving the chains, one or more of said wheels having associated therewith frame controlling mechanism including a series of frame-engaging members disposed circumferentially of the wheel and moving therewith, said members having active and inactive positions, and means to move them into and out of active position to engage and release frames passing the wheel. 85
- 15 8. Conveying mechanism for tufting frames of looms, comprising carrier chains, wheels for supporting and moving the chains, one or more of said wheels having associated therewith frame controlling mechanism including an annular series of plungers, means slidably supporting the 90 plungers for travel with the wheel, spring means to retract the plungers, and cam means for extending them sequentially into engagement with frames passing the wheel. 95

9. In a tufted-fabric loom, in combination with the pattern chains, their wheels and the yarn-frames on and between the chains, guides adapted to underlie portions of the chains during substantially horizontal runs thereof, and means supporting the guides for yielding movement in the direction crosswise the chains. 100
10. In a tufted-fabric loom, in combination with the pattern chains, their wheels and the yarn-frames on and between the chains, guides adapted to underlie portions of the chains during substantially horizontal runs thereof, and means supporting the guides for yielding movement in the direction crosswise the chains, including members engageable with the chain sides to guide them laterally and assist in maintaining the supported frames in alignment. 105
11. In a tufted-fabric loom, in combination, a pattern chain supporting framework including top beams along which the chains run, chain-guiding ways extending along the beams, supports therefor on the beams, and means connecting the ways with their supports but permitting them to yield crosswise the chains. 110
